(57) **CLAIM**

The ornamental design for a dust bag for cleaning appliance, as shown and described.

DESCRIPTION

1. Dust bag for cleaning appliance

FIG. 1.1 is a front view illustrating a dust bag for cleaning appliance;

FIG. 1.2 is a back view illustrating the dust bag for cleaning appliance;

FIG. 1.3 is a left view illustrating the dust bag for cleaning appliance;

FIG. 1.4 is a right view illustrating the dust bag for cleaning appliance;

FIG. 1.5 is a top view illustrating the dust bag for cleaning appliance;

FIG. 1.6 is a bottom view illustrating the dust bag for cleaning appliance;

FIG. 1.7 is a front perspective view illustrating the dust bag for cleaning appliance;

FIG. 1.8 is a partially enlarged view illustrating a part "A" circled in FIG. 1.7;

FIG. 1.9 is a top perspective view illustrating the dust bag for cleaning appliance; and

FIG. 1.10 is another front perspective view illustrating the dust bag for cleaning appliance.
